(57) **CLAIM**

The ornamental design for an electrical receptacle for a desktop/work surface as shown and described.

DESCRIPTION

FIG. 1 is a perspective view of an electrical receptacle for a desktop/work surface, showing our new design;

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof; and,

FIG. 8 is a perspective view of the electrical receptacle for a desktop/work surface, the electrical receptacle for a desktop/work surface being in an undeployed configuration.

In the drawings, the broken lines are for the purpose of illustrating portions of the electrical receptacle for a desktop/work surface that form no part of the claimed design.
